UNITED STATES PATENT OFFICE.

EMIL HENRIK WIDEGREN AND KLAS AUGUST WIDEGREN, OF ALBY, SWEDEN.

AUTOGRAPHIC TELEGRAPHY.

1,171,822.

Specification of Letters Patent. Patented Feb. 15, 1916.

Application filed December 20, 1913. Serial No. 807,917.

To all whom it may concern:

Be it known that we, EMIL HENRIK WIDEGREN and KLAS AUGUST WIDEGREN, subjects of the King of Sweden, and both 5 residents of Alby, Sweden, have invented new and useful Improvements in Auto-graphic Telegraphy, of which the following is a specification.

The present invention relates to such systems for actuating electric apparatus at a distance in which there are used pulsations of alternating polarity obtained from a source of continuous electric current for actuating the receiving apparatus. In such 15 systems it may in many cases be desirable to be able to effect a diplex action without increasing the number of wires, for instance to effect in a writing telegraph or in an apparatus recording at a distance, besides the 20 movement proper of the pen, also its lifting from the writing plane for spacing or changing of lines.

The present invention has for its object to provide a method of and means for effecting 25 such a diplex action, the method chiefly consisting in this, that the receiver is provided with an apparatus operating in the ordinary way for the pulsating current, independently of the polarity of the latter, and with 30 an apparatus operating by a difference between the effective value of the positive and negative pulsations but remaining unaffected when the positive and negative pulsations are the same; and that, when said 35 diplex action has to be effected, there is produced in the transmitter by means of arbitrary arrangements, an unbalancing of the effective value of the positive and negative pulsations, which is sufficient to cause the 40 latter apparatus at the receiver to operate, without the normal operation of the former apparatus being disturbed.

The invention will be more particularly described here below with reference to the 45 accompanying drawings, its general principles being first explained and then some applications in detail described.

Figures 1 and 2 show two different forms of pulsation curves. Figs. 3 to 5 show different manners of effecting unbalancing of active pulsations. Figs. 6 and 7 show different manners of effecting unbalancing of passive pulsations. Fig. 8 shows a double unbalancing of the pulsations. Fig. 9 illustrates diagrammatically an apparatus for

effecting the unbalancing of the pulsations shown in Figs. 1 to 3. Figs. 9^a, 9^b, and 9^c, show modifications of the apparatus according to Fig. 9. Fig. 10 illustrates diagrammatically an apparatus for effecting the unbalancing shown in Fig. 4. Fig. 11 shows another apparatus for effecting the unbalancing shown in Fig. 6, and Fig. 12 an apparatus for effecting the unbalancing according to Fig. 7. Fig. 13 shows an application of the invention to a writing telegraph according to our U. S. Patent No. 1054811 for effecting, besides the writing movements of the recording pen at the receiving apparatus, also the lifting of the recording pen 60 from the writing plane. Figs. 14 and 15 show the pulsation curves used in the application of the invention shown in Fig. 13.

In Figs. 1 and 2 are shown two different forms of pulsation curves which are the superposition for the application of the invention. Fig. 1 shows positive and negative pulsations separated by currentless intervals, while Fig. 2 shows positive and negative pulsations separated by weaker pulsations, which have to assist in discharging and recharging the line, thus reducing the damping influence of the line capacity on the open current. In both figures the zero-line is indicated by 1—2, the limit of action of the 75 receiving apparatus (for instance a relay), i. e. the minimum value of the pulsation that is to be reached in order to make the receiving apparatus operative, being indicated on the positive side by the line 3—4 and on the negative side by the line 5—6. In Fig. 1 the pulsations are indicated by 7—10, 11—14, 15—18 and 19—22. In Fig. 2 there are two kinds of pulsations, on the one hand such as do not reach the limit of action of the 80 receiving relay, thus not influencing the relay, and on the other hand such as reach up to or beyond this limit of action, thus influencing the relay. The former are here 85 below called "passive," the latter "active" 90 pulsations. The curve begins with a passive pulsation at 23, lasting between 23 and 24, where it turns into the active pulsation 25—28. Both of these pulsations are positive. At 28 there begins a new passive pulsation, which lasts between 29 and 30, where 95 it turns into the active pulsation 30—33. Both of these pulsations are negative. Other passive pulsations are 33—35 and 38—40 and the other active pulsations 35—38 100

105 110

and 40—43. Both the active and the passive pulsations thus have alternating polarity.

As appears from Figs. 1 and 2, the pulsation curve is symmetrical or balanced in relation to the zero-line, and it is just this character that is to be changed according to the present invention, when a diplex action is to be effected. If a pulsating current of the kind shown in Figs. 1 or 2 is led through a common continuous current meter (based on the principle of Depréz-d'Arsonval), the meter will, provided it is sufficiently damped against the separate pulsations, give no deflection. The positive and negative parts of the current are the same and neutralize the influence of one another on the meter. If on the other hand equilibrium between the positive and the negative parts of the curve is in any way disturbed, the meter will give a deflection, the size of which depends on the difference between the magnetizing influence of the positive and negative pulsations on the meter. It should be observed that such a disturbance of the equilibrium between the positive and the negative parts of the curve can take place without the normal influence of the separate pulsations on the relay of the receiving station necessarily being disturbed.

The indicated unbalancing between the positive and negative parts of the pulsation curve can be effected in several different ways, some typical cases of which are shown in Figs. 3—7.

According to Fig. 3 the disturbance of the equilibrium is effected by reducing the height of the positive pulsations 7—10. Of the curve there is shown only one positive pulsation 7—10 and one negative pulsation 11—14 both of one and the same size; the zero-line is indicated by 1—2 and the limit of action of the receiving relay by 3, 4 and 5, 6. The line 44—45 cuts off a part of the positive pulsation. By removing the part 44, 8, 9, 45 of every positive pulsation one thus can disturb the equilibrium between the positive and negative part of the curve, thereby effecting at the receiving station a diplex action of the pulsations transmitted.

By removing the part 44, 8, 9, 45 the influence of the pulsation on the chief relay of the receiving station is not changed, if only the curtailing does not extend below the limit of action 3, 4 of this relay.

In Figs. 4 and 5 the said unbalancing of the curve is effected by another kind of curtailing the pulsations on the one side of the zero-line. In both figures the zero-line is indicated by 1—2, the limit of action by 3, 4 and 5, 6 and the pulsations by 7—10 and 11—14. In Fig. 4 the curtailing has the form 46—49, in Fig. 5 the form 50—52. In both cases the curtailing does not extend below the limit of action 3, 4. If the pulsating current has passive pulsations, as

shown in Fig. 2, the latter may be curtailed in the way described above.

Figs. 6 and 7 show examples thereof. In both figures the 0-line is indicated by 1, 2, the limit of action by 3, 4 and 5, 6 and the uncurtailed pulsations by 23—28 and 29—33. According to Fig. 6 the unbalancing is effected by a cutting out 53—56 in the positive passive pulsation. The cutting out 53—56 in the passive pulsation may extend unto the 0-line and even beyond the latter, as is shown in Fig. 7. Of course, instead of alternating between balancing and unbalancing the curve one can alternate between unbalancing either in the positive or the negative direction, thus effecting the diplex action aimed at. In fact this will be the same as described above, but the unbalancing will be twice as effective in the receiving apparatus operating for the unbalancing. In Fig. 8 there is shown a pulsation curve with such an unbalancing. The 0-line is indicated by 1, 2 and the limits of action by 3, 4 and 5, 6. In unbalancing in the positive direction the respective pulsations have the form 7—10 and 11, 61, 62, 14 and in negative unbalancing 7, 44, 45, 10 and 11—14. The unbalancing shown in Fig. 8 is a repetition of the unbalancing according to Fig. 3 at the pulsations on both sides of the 0-line. One may proceed in the same way with the unbalancings shown in Figs. 4—7. As the difference between the positive and negative pulsations in such a double unbalancing in the one case becomes positive and in the other case negative, the receiving apparatus working by these differences will make a deflection to the one or the other side of its zero-position according as the difference is positive or negative.

The arrangements necessary to effect the changes of the pulsation curve above described and to make these perceptible at the receiving station may be carried out in several different manners and in Figs. 9—12 are shown some constructional forms of such arrangements.

In Fig. 9, A is a transmitting station and B a receiving station. At the transmitting station A there is arranged a disk or cylinder 61 provided with bars 62, 63, 64, 65 insulated from each other (being in the drawing supposed to be laid out in a plane). On the axle 66 of the disk or cylinder 61 there are arranged slip rings 67, 68, 69 with sliding brushes 70, 71, 72 respectively. The bar 62 is connected with the slip ring 69, bar 63 with slip ring 67, bar 64 with slip ring 68, either directly or by connection with bar 62, and bar 65 with slip ring 68. The sliding brush 70 is by a wire 73 connected with the positive side of the current source 74, the middle of which is connected to earth by a wire 75. The sliding brush 71 is by a wire 76 connected with the nega-

5 tive side of the current source 74 and the sliding brush 72 is by a wire 77 connected to earth. In the wire 73 there is arranged a switch 78, by means of which a resistance 79 connected in series to the wire 73 can be short-circuited. Against the disk or cylinder 61 there is bearing a sliding brush 80, which is connected with the connecting line 81. In the connecting line there are at the 10 receiving station B inserted a relay 82 being so sensitive as to be influenced by every separate active pulsation, and a magnet coil 83 having a polarized armature 84 which is so damped by its own weight and by the 15 magnetic field, that it cannot be influenced by the separate pulsations. The armature 84 is kept in a certain idle position by a spiral spring 85. The relay 82 has an armature 86 which is kept away from the magnet 20 by a spring 87. Finally the connecting line 81 is at B connected to earth by the wire 88.

25 The operation of the arrangement according to Fig. 9 is as follows. When the disk or cylinder 61 rotates in the direction indicated by the arrow, the brush 80 is passed by the bars 62, 63, 64, 65 in the order thus indicated. Through the bar 62 no pulsation is transmitted, as this bar by the slip ring 69, sliding brush 62 and wire 77 is connected 30 to earth. When the brush 80 is passed by the bar 63, there is transmitted through the wire 73, brush 70, slip ring 67, bar 63 and brush 80 a pulsation from the positive side of the current source 74. In this pulsation 35 the strength of current varies according as the resistance 79 is short circuited by the switch 78 or not. In the latter case the pulsation becomes lower, in the former higher. When the brush 80 is passed by 40 the bar 64, no pulsation flows, because this bar by slip ring 69, brush 72 and wire 77 is connected to earth. When the sliding brush 80 is passed by the bar 65, a pulsation from the negative side of the current source 74 45 is transmitted through wire 76, brush 71, ring 68, bar 65 and brush 80. If the resistance 79 is short circuited, the positive pulsation transmitted through the bar 63 will be of the same height as the negative 50 pulsation transmitted through the bar 65, and the pulsation curve will have the appearance shown in Fig. 3 and indicated by 7-14. The resistance 79 is so proportioned, that when it is connected up, the positive pulsation in Fig. 3 gets the appearance 55 7, 44, 45, 10. Whether the resistance 79 is connected up or not, the relay 82 will be actuated by every pulsation and the armature attracted. During the intervals of the pulsations the armature is kept away from the magnet by the spiral spring 87. The other apparatus 83 at the receiving station operates in a quite different way. When the 60 resistance 79 of the transmitting apparatus 65 is short circuited, the pulsation curve thus

being balanced, the magnetizing effects of the positive and negative pulsations neutralize each other, so that the pulsations have no influence on the polarized armature 84. This therefore remains in its idle position 70 just as when the coil 83 was currentless. If, on the other hand, the resistance 79 is connected up by opening the switch 78, the positive and negative pulsations do not neutralize each other, and therefore the coil 75 83 is capable to produce a certain magnetic effect on the armature 84, which thus is attracted or repelled from its idle position, thus being able to carry out a desired work, for instance effect the closing or breaking 80 of a local circuit or the like. If the resistance 79 is again short circuited, the armature 84 retakes its former position.

In order to produce the unbalancings of the pulsation curve shown in Figs. 4-8, 85 chiefly the same arrangement is necessary as shown in Fig. 9; here below only such additional arrangements or changes as are necessary, are described.

90 For the unbalancing according to Fig. 4 it is necessary that the bar giving the positive pulsation is in the middle provided with a piece 88, Fig. 10, insulated from the other parts of the bar and connected to a separate slip ring 67^a with sliding brush 70^a, which 95 by the wire 73^a is connected with the wire 73. The resistance 79 and the switch 78 are inserted in the wire 73^a, while the wire 73 runs direct to the brush 70. The bar 63, with the exception of the part 88, receives 100 as before current through the slip ring 67, sliding contact 70 and wire 73 from the positive side of the current source 74. When the resistance 79 is short circuited, the part 88 of the bar 63 gives just as high a pulsation 105 as the other parts of the bar 63; when the switch 78 is open and the resistance 79 is connected up, the positive pulsation from the part 88 decreases, so that this pulsation gets the form 7, 8, 46, 47, 48, 49, 9, 10 110 (Fig. 4).

In order to effect the unbalancing shown in Fig. 5 there is required only such a modification of the arrangement shown in Fig. 10, that the bar part 88 is not placed at the 115 middle of the bar 63, but at its end, while slip rings, wires etc. remain quite unchanged.

In order to effect the unbalancing according to Fig. 6 there are required some minor 120 alterations which are illustrated in Fig. 11. In this case also the bar 62 is at the middle provided with an insulated part 89. The bar 62, which according to Figs. 9 and 10 is by means of a slip ring connected to 125 earth, is here through the resistance 90 connected to the bar 63. The bar 64, which in the same way according to Figs. 9 and 10 is connected to earth, is here by means of the resistance 91 connected to the bar 65. A 130

further slip ring 67^b with sliding brush 70^b has been introduced together with the wire 73^b with the switch 78^b and the resistance 79^b.

The bar 63, which here consists of two parts, is as before in connection with the slip ring 67 and through this with the positive side of the current source 74. The resistance 90 is so proportioned that the current flowing through the bar 62 corresponds to the strength of current of a passive pulsation (in Fig. 6 corresponding to the pulsation 23, 24, 25). Also the resistance 91 is so proportioned, that the bar 64 gives a passive pulsation. The bar part 88 is, as in Fig. 10, connected to the slip ring 67^a, and the bar part 89 is connected to the slip ring 67^b. The resistance 79^a and the switch 78^a act in the same way as in Fig. 10, and the resistance 79^b effects, when the switch 78^b is closed, that the bar part 89 receives the same current as the other parts of the bar 62. When the switch 78^b is open, the bar part 89 does not receive any current. The pulsation curve, therefore, when the switches 78^a and 78^b are closed, gets the appearance 23-33 in Fig. 6, being balanced; when the same switches are open, the curve gets the appearance 23, 24, 53, 54, 55, 56, 25, 26, 57, 58, 59, 60, 27, 28, 29, 30, 31, 32, 33, being unbalanced.

If the passive pulsation has to be changed in the unbalancing, as is shown in Fig. 7, a further wire 76^a with the resistance 92 is added to the arrangement shown in Fig. 11, as is illustrated in Fig. 12. The switch 78^b is here arranged to make contact in two directions. The slip ring 67^b and thereby the bar part 89 will be connected to the negative side of the current source 74 in the one case and to the positive side in the other case. The resistances 79^b and 92 are of the same strength, and therefore the current in both cases becomes the same but of different polarity.

In all the arrangements described above the changing of the pulsation curve in order to effect the unbalancing has been made only on the positive side. If the unbalancing has to be made double, as is shown in Fig. 8, one has to make the same arrangements also on the negative side, *i. e.* to introduce the same wires, the same resistance and the same arrangements for the bars 64 and 65 as for the bars 62 and 63. When the arrangement on the one side is in operation, the other one is not in operation and vice versa.

In Fig. 13 is shown the application of the invention to a handwriting telegraph system according to our U. S. Patent No. 1054811 for the purpose of regulating the movement of the recording pen of the receiving station to and from the writing plane. A is the transmitting and B the receiving station. The cylinder 93 is shown developed in a plane and has four bars indi-

cated by 94, 95, 96, 97. On three of these bars there is an insulated bar part 98, 99 and 100 respectively. At the cylinder 93 are provided brushes 101, 102, which are movable axially and placed diametrically opposite each other, and connected with the writing arms and regulated by the movement of the latter, as described in our said U. S. Patent No. 1054811. The writing arms are not shown in Fig. 13.

On the axle 103 of the cylinder 93 are placed two slip rings 104, 105, being likewise shown as developed in a plane. The slip ring 104 consists of the part 106 and of the part 107, on the periphery of which is provided the insulated bar 108, extending along half the periphery. The part 106 is insulated from the part 107. Against the slip ring 104 bear four brushes 109, 110, 111, 112, which are insulated the one from the other. The brushes 111 and 112 are placed diametrically opposite each other and so situated in relation to the brushes 101 and 102 on the cylinder 93, that when these just have come on the bars 94 and 96 respectively, the brush 111 is leaving and the brush 112 is going over to the bar 108. The slip ring 105 is made exactly similar to the slip ring 104; it consists of the parts 113 and 114, and the insulated bar 115. Against the slip ring 105 bear four brushes 116, 117, 118, 119, being insulated the one from the other. The brushes 118 and 119 are placed diametrically opposite each other and so situated in relation to the brushes 101 and 102 on the cylinder 93, that when these have entered on the bars 94 and 96 respectively, the brush 118 just has left and the brush 119 just has entered upon the bar 115.

The bars and the brushes are in the following manner connected with each other and with the current source 74. The bars 94 and 96 are through the wire 120 connected with the ring part 114. The bars 95 and 97 are through the wire 121 connected with the ring part 107. The bar 98 is through the wire 122 connected with the ring part 106 and the bar part 99 is through the wire 123 connected with the ring part 113. The bar part 100 is through the resistance 124 connected with the bar 97. The brush 101 is connected with the connecting line 125 and the brush 102 is connected with the connecting line 126. The brush 111 is through the wire 127 connected with the positive side and the brush 112 through the wire 128 with the negative side of the current source 74. The brush 118 is through the wire 129 connected with the positive side and the brush 119 through the wire 130 with the negative side of the current source 74, but on a lower potential than the brushes 111 and 112 respectively.

The writing table 131 at the transmitting

station is movable up and down. It is supported by the spring 132 and may in the writing operation be pressed down until it strikes the abutment 133. During this movement two contact devices 134 and 135 become operative. When the writing table is in its upper position (not being pressed down), the contact 134 is closed and the contact 135 broken; when the writing table is in its lower position, the contact 134 is broken and the contact 135 closed. To the contact device 134 are connected wires 136 and 137 running from the brushes 109 and 110 respectively. To the contact device 135 are connected wires 138 and 139 running from the brushes 116 and 117 respectively. A resistance 140 is inserted between the wires 136 and 137.

At the receiving station the connecting lines 125 and 126 are running to the windings of the diaphragm relays 141 and 142 respectively, and to a tubular coil 143 and therefrom to earth. The diaphragm relays 141 and 142 are so arranged, that they act in perfect harmony with the pulsations transmitted through the lines 125 and 126, as soon as the strength of these pulsations amounts to or exceeds a certain minimum strength. The said relays thereby close and break local circuits 144, 145 and 146, 147, which are shunted to other circuits 148, 149 and 150, 151 respectively, containing a continuous current source 158 and coils 152, 153, which are rotatably journaled in a constant magnetic field created by electromagnets 154 and 155, the coils 156, 157 of which are supplied with current from the continuous current source 158 through the circuit 159. The coils 152 and 153 serve in a well known manner to move by the arms 160, 161 and links 162, 163 the recording pen 164 for effecting the writing, pulsating currents flowing during the operation of the diaphragm relays through said coils, the effective value of which currents and the tubing of the coils caused thereby being dependent on the pulsations passing through the connecting lines 125 and 126.

In order to move the recording pen 164, which in the form of construction shown is supposed to write on the lower side of a transparent paper 201, to and from the writing table, as is necessary for instance in spacing and changing lines, the following arrangements are combined with the coil 143 at the receiving station. The tubular coil 143, which consists of two parts having the same number of turns wound in opposite directions, is suspended by means of springs 165 and 166 in a constant magnetic field, created by a central iron core 167, which passes freely through the coil 143 and is provided with a coil 168, connected to the circuit 159, and an iron core 169 which incloses the coil 143 without being in con-

tact with the same. The coil 143 supports a contact spring 170, which, when the coil 143 is in its normal position, closes a contact 171 in a circuit 172, 173, which forms a short circuit to the winding of a relay 174. The armature 175 of the relay 174 is pivotally journaled at 176 and supports a frame 177, which grasps over the links 162, 163, so that it will pull the recording pen 164 from the paper when the armature of the relay is attracted. The contact spring 170 is suitably made rather weak, so that, when by the influences of the pulsating currents passing through the coil 143 it gets into vibrations, it can form a node of oscillation near its front end, where the contact 171 is arranged, in order to secure a good contact, independently of said vibrations.

The arrangement shown in Fig. 13 and described above operates as follows: When the writing table 131 on account of writing going on is pressed down, there is transmitted through the brush 101 a continuous series of pulsations of the form shown in Fig. 14. The pulsation curve is indicated by 178—196, the zero line by 1, 2 and the limit of action of the relays 141, 142 by 3, 4 and 5, 6. The different pulsations arise in the following manner. When the brush 101 connects with the bar 94, there flows a current 178 through the line 125 in the following way: From the lower positive potential of the current source 74 to 129, 118, 114, 120, 94, 101, 125, 141, 143 and through the earth wire back to the middle of the current source 74. This current gives a positive passive pulsation of the form 178—180, Fig. 14. When the brush 101 enters the bar 95, there flows a current through the line 125 in the following way: From the higher positive potential of the current source 74 to 127, brush 111 (which now has left the bar 108), 107, 121, 95, 101, 125, 141, 143 and through the earth wire back to the middle of the current source 74. When the brush 101 passes the bar part 98, this circuit is so changed, that the current from the ring 107 passes through the brush 110, wire 137, resistance 140 (the contact 134 being open on account of the writing table 131 being pressed down), wire 136, brush 109, ring 106, wire 122, bar part 98, brush 101 and therefrom through the line 125. During the time the brush 101 passes the bar 95 and the bar part 98, the active positive pulsation 180—187 consequently is transmitted, which at its middle has a depression 182—185 caused by the temporary connecting up of the resistance 140. The resistance 140 is so proportioned that the said depression does not reach the limit of action of the relay 141, thus being without any influence on the operation of the latter. When the cylinder 93 with the rings 104, 105 has rotated half a revolution, the brush 101 enters the bar 96, and now

there flows a current through the line in the following way: From the lower negative potential of the current source 74 to 130, 119, 114, 120, 96, 101, 125, etc., as before. 5 When passing the bar part 99, this circuit is changed in the following manner: From the ring 114 the current passes through 117, 139, 135, 138, 116, 118, 123, 99 to the brush 101, etc., but as the resistance in this path of 10 current is practically the same as that of the path of current through the bar 96, the strength of current remains unchanged. The pulsation transmitted will be a negative pulsation, which does not reach the limit 15 of action 5—6 and is indicated in Fig. 14 by the part 187—189 of the pulsation curve. When the brush 101 enters the bar 97, there flows a current through the line 125 in the following way: From the higher negative 20 potential at the current source 74 to 128, 112, 107, 121, 97, 101, 125, etc., as before. When the brush 101 passes the bar part 100, this path of current is changed in such respect that the current from the bar 97 passes 25 through the resistance 124 and the bar part 100 to the brush 101. While the brush 101 is passed by the bar 97 and the bar part 100, there consequently is transmitted through the line 125 the active negative 30 pulsation 189—196, which at its middle has a depression 191—194 (Fig. 14), caused by the resistance 124. The resistance 124 is of the same value as the resistance 140, so that the depressions 182—185 and 191—194 will 35 be of one and the same size. The pulsations at these depressions should not reach the limit of action, as in such a case one runs the risk, that the active pulsation does not act as a continuous pulsation but allows the 40 diaphragm relay at the receiving station to release its diaphragm armature during the pulsation. If the depression of the pulsation is sufficiently narrow, this danger, however, is excluded, and in such case the depression may extend to the 0-line. The 45 capacity always present in the connecting line then effects that the depression in fact does not reach down to the 0-line, and the inertia of the armature assists, for the rest, in preventing the latter from leaving the 50 magnet at a short depression of the pulsation.

Supposing that the pen at a space between two words is lifted from the writing 55 table 131, so that this by the spring 132 can be brought into its upper position, the following changes of the pulsation curve take place. The contact 134 is closed, that is to say, the resistance 140 will be short circuited and thereby the depression 182—185, Fig. 14, previously existing in the positive 60 pulsation, ceases. The contact 135 on the other hand will be broken. This causes an 65 interruption of the supply of current to the bar part 99, and therefore a depression

197—200, Fig. 15, extending to the 0-line arises in the part 187—189 of the pulsation curve, when the brush 101 passes the bar part 99. When the writing table 131 is in its upper position, the pulsation curve thus 70 obtains the appearance shown in Fig. 15. The positive pulsation has no depressions; the negative pulsation has the depressions 197—200 and 191—194.

When the pulsating current has the appearance shown in Fig. 14 and passes through the winding of the coil 143, the current, provided the coil is sufficiently damped against vibrations, has no influence on the coil, the positive and negative pulsations 75 being entirely equal and therefore tending with the same power to move the coil in opposite directions. The coil therefore remains in the position determined by the springs 165, 166, in which the contact 171 80 is closed, so that the relay 174 is currentless. If on the other hand the current has the appearance shown in Fig. 15, *i. e.*, if the curve is unbalanced, it will when passing the coil 143 have the influence that the coil 85 is moved longitudinally. Such as the direction of the current here is supposed in relation to the magnetic field between the iron cores 167 and 169, the coil moves to the right, so that the contact 171 is opened. The 90 winding of the relay 174 will thereby be passed by the current flowing in the circuit 159, so that the relay 174 will be excited, attracting its armature 175, which then by the frame 177 pulls the recording pen 164 95 from the writing table 201. As the unbalancing of the curve took place at the same time as the writing table 131 took up its upper position, *i. e.*, when the recording pen was lifted from the same, the two recording pens, the one at the transmitting station and the other at the receiving station, will leave their writing tables simultaneously, which is the thing aimed at by the arrangement. The unbalancing introduced 100 will not have any influence on the normal operation of the relay 141, and the movement of the recording pen 164 sidewise therefore takes place independently of whether it is in contact with the writing 105 table 201 or not. If now the pulsations flowing through the brush 102 on the connecting line 126 are examined, one will find that the pulsation curve will be quite analogous with the one previously described, with the exception only that it obtains its unbalancing in the opposite direction. The former received at the unbalancing chiefly positive current; the latter receives chiefly negative current. It is on account of this fact that the two 110 windings of the coil 143, as described above, are wound in opposite directions. The two unbalancings are thereby brought into coöperation and the coil 143 thereby obtains a 115 stronger deflection than if the unbalancing 120

125 130 135 140 145 150 155 160 165 170 175 180 185 190 195 200

would take place only with regard to the current of the one connecting line. It should be observed that the simultaneous pulsations in the two connecting lines by the arrangement described above always obtain the same polarity; by a simple variation of the arrangement one can bring simultaneous pulsations to have opposite polarity. One can also, if desirable, use unbalancing of one and the same sign at the pulsations of the two lines 125 and 126, when the lifting of the pen has to take place, in which case the two windings of the coil 143 of course should be wound in the same direction in order to coöperate.

In the forms of construction described above the unbalancing of the pulsation curves is effected by connecting up a resistance in the circuit for the one or both of the directions of current. The unbalancing can also be effected by changing the positive or the negative potential or both of them at the current source of the transmitting station, as is shown in Figs. 9^a, 9^b, and 25 9^c illustrating modified forms of the apparatus according to Fig. 9. In Fig. 9^a the brush 70 may, by means of a switch 210, be connected up to the positive side of the current source 74 or to a point thereof of 30 lower potential. In Fig. 9^b an additional current source 211 may, by means of two switches 212 and 213, be cut in between the brush 70 and the current source 74 in such manner that it either increases or decreases 35 the action of the current source 74. According to Fig. 9^c a switch 214 cuts in or out an electric valve or electrolytic cell 215, which offers a great resistance for the one direction of current but a small resistance 40 for the other direction, so that an unbalancing of the pulsation curve is effected, when the valve or the cell is connected up in the line circuit 81.

Having now described our invention, what 45 we claim as new and desire to secure by Letters Patent is:

1. Method of producing a diplex effect in actuating electric apparatus at a distance, consisting in generating a series of positive 50 and negative pulsations from a source of continuous current, varying the relation of the magnetizing effects of the positive and negative pulsations, effecting a magnetizing effect corresponding to the sum of the positive and negative pulsations, and effecting another magnetizing effect corresponding to the difference between the positive and negative pulsations.

2. In means for producing a diplex effect 60 in actuating electric apparatus at a distance by means of pulsating electric currents of alternating polarity obtained from a source of continuous current, the combination of a sender arranged to transmit a continuous 65 series of pulsations of alternating polarity

from the said source, means for varying the proportion between the effective values of the positive and negative pulsations in a certain series of pulsations, a receiving relay, means for passing through the said relay the pulsations transmitted from the sender, means for causing the said relay to operate independently of the changes of polarity and the variation of the proportion between the effective values of the positive and the negative pulsations, another polarized receiving relay, and means for actuating the last named relay only when the said proportion is varied, substantially as and for the purpose set forth. 80

3. In means for producing a diplex effect in actuating electric apparatus at a distance by means of pulsating electric currents of alternating polarity obtained from a source of continuous current, the combination of 85 a sender arranged to transmit a continuous series of pulsations of alternating polarity from the said source, means for varying the proportion between the effective values of the positive and the negative pulsations in a 90 certain series of pulsations, a receiving relay, means for passing through the said relay the pulsations transmitted from the sender, means for causing the said relay to operate independently of the changes of polarity 95 and the variation of the proportion between the effective values of the positive and the negative pulsations, another polarized receiving relay, means for actuating the last named relay only when the said proportion 100 is varied, and means for periodically varying, at the sender, the resistance of the circuit for any direction of current, substantially as and for the purpose set forth. 105

4. In means for producing a diplex effect 110 in actuating electric apparatus at a distance by means of pulsating electric current of alternating polarity obtained from a source of continuous current, the combination of a sender arranged to transmit a continuous 115 series of pulsations of alternating polarity from the said source, means for varying the proportion between the effective values of the positive and negative pulsations in a certain series of pulsations, a receiving relay, means for passing through the said relay the pulsations transmitted from the sender, means for causing the said relay to operate independently of the changes of polarity 120 and the variation of the proportion between the effective values of the positive and the negative pulsations, another polarized receiving relay, means for actuating the last named relay only when the said proportion 125 is varied, and means for changing the potential of the source of current for the different directions of the pulsations, substantially as and for the purpose set forth.

5. In means for producing a diplex effect 130 in actuating electric apparatus at a distance

by means of pulsating electric currents of alternating polarity obtained from a source of continuous current, the combination of a sender arranged to transmit a continuous series of pulsations of alternating polarity from the said source, means for varying the proportion between the effective values of the positive and negative pulsations in a certain series of pulsations, a receiving relay, 10 means for passing through the said relay the pulsations transmitted from the sender, means for causing the said relay to operate independently of the changes of polarity and the variation of the proportion between 15 the effective values of the positive and the negative pulsations, another polarized receiving relay, means for actuating the last named relay only when the said proportion is varied and an electric valve inserted in 20 the circuit and arranged to offer greater resistance for the one direction of current than for the other, substantially as and for the purpose set forth.

6. In means for producing a diplex effect 25 in actuating electric apparatus at a distance

by means of pulsating electric currents of alternating polarity obtained from a source of continuous current, the combination of a sender, a recording pen in said sender arranged to control variations of the proportion between the effective values of the positive and negative pulsations, a receiver, 30 a recording pen in said receiver, a writing table operated upon by the recording pen of the receiver, a relay in the receiver arranged to move its recording pen to and from the last named writing table by the variations of the pulsations arriving to the receiver and actuating continuously the recording pen in accordance with the writing 35 pen of the sender, substantially as and for the purpose set forth.

In testimony that we claim the foregoing as our invention, we have signed our names in presence of two subscribing witnesses.
